US0D1036617S

(12) **United States Design Patent** (10) **Patent No.:** **US D1,036,617 S**
(45) **Date of Patent:** **** Jul. 23, 2024**

(54) **SEPTIC CHAMBER END CAP**

(71) Applicant: **Prinsco, Inc.**, Willmar, MN (US)

(72) Inventors: **Zachary J. Jemming**, Willmar, MN (US); **Rory M. Shea**, Atwater, MN (US)

(73) Assignee: **Prinsco, Inc.**, Willmar, MN (US)

(**) Term: **15 Years**

(21) Appl. No.: **29/827,124**

(22) Filed: **Feb. 17, 2022**

(51) **LOC (14) Cl.** **23-01**

(52) **U.S. Cl.**

USPC **D23/207**

(58) **Field of Classification Search**

(57) **CLAIM**

The ornamental design for a septic chamber end cap, as shown and described.

DESCRIPTION

FIG. 1 is a perspective view of a septic chamber end cap showing our new design;

FIG. 2 is a front elevational view;

FIG. 3 is a rear elevational view;

FIG. 4 is a left side elevational view;

FIG. 5 is a right side elevational view;

FIG. 6 is a top plan view; and,

FIG. 7 is a bottom plan view.

Broken lines in FIGS. 1, 2, 4, 6, and 7, illustrate environmental subject matter and form no part of the claimed design. Additional broken lines in FIG. 7 illustrate portions of the septic chamber end cap that form no part of the claimed subject matter.

1 Claim, 7 Drawing Sheets

US D1,036,617 S
